UNITED STATES PATENT OFFICE.

GEORGE M. DONER, OF TOLEDO, OHIO.

FILING-RECEPTACLE.

No. 892,141.

Specification of Letters Patent. Patented June 30, 1908.

Application filed June 24, 1907. Serial No. 380,449.

To all whom it may concern:

Be it known that I, GEORGE M. DONER, a citizen of the United States, and a resident of Toledo, in the county of Lucas and State of Ohio, have invented a certain new and useful 5 Filing-Receptacle; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to folders or other 15 receptacles for the filing of papers or other articles, and is particularly intended for the filing of the tariff sheets used by railroads doing an inter-changing business, but is not restricted to such use, as it may be used for 20 the filing of any articles for which it may be appropriate.

It is the custom for all railroads, which interchange business, to issue tariffs mutually agreed to by all of the interested lines. For 25 example, if a Michigan line contracted for freight from Detroit to New York, the shipment to travel via Toledo, they could route the shipment via any of the Toledo-New York lines, of which there are many, provided they had tariffs in effect with the selected line. As there are hundreds of different routes and hundreds of different commodities it will readily be seen that it requires a multitude of tariffs to carry on the 30 business, and as there are no two roads which have adopted either exactly the same size or same form of tariffs, it will also be apparent that the question of filing the tariffs of the different roads so as to be readily accessible 35 is a very difficult one.

The object of my invention is the provision in a receptacle of this class, of a tongue which is secured interiorly to the bottom thereof and projects outwardly through a side or end 45 of the receptacle in the plane of the bottom, and which is adapted both to receive a designation of the contents of the receptacle, thus directing a person to the package he is looking for, and to form a finger-grip by means of 50 which the receptacle may be withdrawn from the file case.

The invention is fully described in the following specification and illustrated in the accompanying drawing, which shows a per-

spective view of the folder embodying the 55 features of my invention.

Referring to the drawing, 1 designates the upper and 2 the lower leaf or half of the wrapper comprising my invention, which parts are folded upon each other along a line 60 3. The upper half 1 is preferably made of greater length than the lower half, as shown in Fig. 1, to compensate for the thickness of the contents, as the lower half is intended to remain flat throughout its length while the 65 closed end of the upper half curves to conform to the thickness of the papers held therein.

Either side of the upper leaf 1 of the receptacle, or both sides if desired, may be printed 70 as shown to form an index sheet for the entry of the contents of the package, thus making it possible to readily locate any paper desired without running through the entire contents of the receptacle.

Projecting from the closed end of the receptacle is a tongue 4, which is intended to serve both as a tag upon which the subject of the contents of the package may be briefly designated, and as a finger-grip to facilitate 80 the withdrawal of the package from between a plurality of other similar packages. As considerable strain is exerted on the tongue when its package is being drawn from beneath a pile of other packages it is important 85 that it be so attached as to lessen the liability of its being torn from its receptacle. In Fig. 1 the tongue is shown as projecting from a transverse strip 5 through a slit 6 provided at the line of fold of the two parts of 90 the folder, said transverse strip being glued or otherwise secured to the lower part 2 with its inner edge approximately coinciding with the line of fold, thus causing a pulling strain 95 to be applied directly to the lower flat leaf 2 instead of to the upper half of the folder. This tongue and its attached strip may be cut from any suitable material. Any suitable information indicative of the contents 100 of the wrapper may be printed on the tongue, such, for instance, as "P. M. R.—Lumber", which shows that the contents relates to the lumber tariff on the P. M. Railroad.

Having thus described my invention, what I claim as new, and desire to secure by Letters Patent, is,—

A filing receptacle having a slit in its end in a plane with the inner surface of its bot-

tom, a tongue projecting outwardly from the receptacle through said slit and having an enlargement on its inner end fixed to the bottom of the receptacle to prevent a withdrawal of the tongue either outwardly or inwardly from the slit, substantially as described.

In testimony whereof I have hereunto signed my name to this specification in the presence of two subscribing witnesses.

GEORGE M. DONER.
